UNITED STATES PATENT OFFICE.

CLEM F. WADE, OF EVANSTON, ILLINOIS.

DESIGN FOR A REFRIGERATOR.

Application filed September 13, 1926. Serial No. 19,052. Term of patent 3½ years.

To all whom it may concern:

Be it known that I, CLEM F. WADE, a citizen of the United States, residing at Evanston, in the county of Cook and State of Illinois, have invented a new, original, and ornamental Design for Refrigerators, of which the following is a specification, reference being had to the accompanying drawing, forming part thereof.

The drawing is a side view in perspective of a refrigerator, showing my new design.

I claim:

The ornamental design for a refrigerator as shown.

In witness whereof, I hereunto subscribe my name this 7th day of September, 1926.

CLEM F. WADE.
